UNITED STATES PATENT OFFICE

ISRAEL SCHLEGEL, OF TOPEKA, KANSAS, ASSIGNOR OF ONE-HALF TO
THOMAS PARKINSON, OF SAME PLACE.

TONGUE-SUPPORT FOR VEHICLES.

SPECIFICATION forming part of Letters Patent No. 335,313, dated February 2, 1886.

Application filed October 30, 1885. Serial No. 181,372. (No model.)

To all whom it may concern:

Be it known that I, ISRAEL SCHLEGEL, a citizen of the United States, residing at Topeka, in the county of Shawnee and State of Kansas, have invented certain new and useful Improvements in Wagon-Tongue Supporters; and I do declare the following to be a full, clear, and exact description of the invention, such as will enable others skilled in the art to 5 to which it appertains to make and use the same, reference being had to the accompanying drawings, and to the letters and figures of reference marked thereon, which form a part of this specification.

15 My invention relates to improvements in that class of devices known as "tongue-supporters," and is intended to provide a device which will relieve the horses' necks of the strain caused by the weight of the tongue, 20 and will also serve to prevent the jolting and jerking of the tongue caused by the unevenness of the roads.

It consists in certain novel features, herein-after fully described, and specifically pointed 25 out in the claims.

In the drawings, Figure 1 shows the device as applied to a wagon-tongue. Fig. 2 is a view of the supporter detached. Fig. 3 shows in detail the block to which the lower end of 30 the supporter is secured; and Fig. 4 shows in detail the knee-brace, which is secured to the under side of the tongue.

A represents the tongue; A', the hounds, and A² the axle. To the under side of the 35 tongue I secure a knee-brace, B, which is composed of a single plate of metal bent at right angles, so as to provide the arm B', which lies flat against the under side of the tongue, and the arm B², depending therefrom. 40 The arm B' is provided with holes B³ B⁴, through which I insert screws, which enter the tongue and secure the knee-brace thereto. Near the forward end of the arm B', I provide the pin B⁴, which enters a suitable notch provided on the under side of the tongue, and aids in holding the knee-brace in position, as 45 will be understood. The depending arm B² of the knee-brace is provided with an opening, B⁵, the purposes of which will be more 50 fully hereinafter described.

A retaining-plate, C, provided with ears

C' C', is secured to the axle by screws inserted through the holes C² C², as will be understood. The ears C' C' are made integral with the plate C, and are placed a proper distance apart midway the ends thereof. The tongue-supporter shaft is pivotally secured between these ears by a bolt, C³, passed through suitable bolt-holes therein, as shown. The tongue-supporter shaft D is held by and between the retaining-plate C and the knee-brace B.

The lower end of the tongue-supporter shaft is pivotally secured between the ears C' C', as before stated. The upper end of the shaft is 65 passed through the opening B⁵ in the depending arm B² of the knee-brace B. The lower end of the shaft D is flattened, so as to fit easily 70 between the ears C' C'. It is made cylindrical throughout the rest of its length, but its diameter is diminished at its upper end, as shown. This smaller portion, D', is inserted through the opening B⁵, and plays therein in the operation of the device.

The outer end of the portion D' is provided 75 with a nut, D², and between the nut D² and the arm B², I place around the shaft a coiled spring, D³. The shaft D is not made on a straight line, but it is bent down at nearly a right angle and up at an acute angle, as shown 80 at D⁴. The main portion D⁵ of the shaft D is screw-threaded, and two nuts, D⁶ D⁷, are placed thereon. Between these nuts and the arm B² of the knee-brace, around the shaft D I place the coil-spring D⁸. Where so desired, 85 a washer can be placed between the nuts D⁶ and the spring D⁸.

The operation of my device will be readily understood. The tongue is raised to the position which it is desired to occupy, and the 90 nuts D⁶ D⁷ adjusted until the tension of the spring D⁸ is sufficient to support it. When the wagon is being drawn along the road, the ruts and other unevennesses of the ground will cause the pole or tongue to swing up and 95 down. The tendency of the spring D⁸ will be to increase or exaggerate this up or down motion. The spring D³ will counterbalance this tendency of the spring D⁸, and the motion of the tongue will be decreased.

In practice it has been found that the ordinary straight tongue-supporter tended to

throw the under side of the axle around backward, and the hounds would be thrown up against the perch and the parts locked together and weakened and often broken. By 5 bending the lower end of the shaft D, as shown, I throw the line of pressure against the center of the axle, and it is thereby kept in its proper position.

Having thus described my invention, what I 10 claim, and desire to secure by Letters Patent, is—

1. In a wagon-tongue supporter substantially as herein shown and described, a supporter-shaft pivotally secured at its lower end 15 to a retaining-plate fastened to the wagon-axle, and having its upper end supported by a knee-brace secured to the under side of the tongue, said supporting-shaft being bent down

at about a right angle and upward, substantially as shown, and for the purposes specified. 20

2. The combination of the tongue, the knee-brace secured to the under side thereof, the axle, the retaining-plate fastened thereto, the tongue-supporter shaft pivotally secured at its lower end to the retaining-plate and loosely supported at its upper end by the knee-brace, coiled springs placed around the shaft on the opposite sides of the depending arm of the knee-brace, and a nut and jamb-nut for regulating the tension of the larger spring, 25 substantially as specified.

In testimony whereof I affix my signature in presence of two witnesses.

Witnesses: ISRAEL SCHLEGEL.
THOMAS PARKINSON,
Wm. OSTERLOH.
